(57) **CLAIM**

The ornamental design for a water floatation device, as shown and described.

DESCRIPTION

FIG. 1 is an upper right front perspective view of a water floatation device;

FIG. 2 is a lower right front perspective view of the water floatation device of FIG. 1;

FIG. 3 is an upper left rear perspective view of the water floatation device of FIG. 1;

FIG. 4 is a lower left rear perspective view of the water floatation device of FIG. 1;

FIG. 5 is a top plan view of the water floatation device of FIG. 1;

FIG. 6 is a bottom plan view of the water floatation device of FIG. 1;

FIG. 7 is a front elevational view of the water floatation device of FIG. 1;

FIG. 8 is a rear elevational view of the water floatation device of FIG. 1;

FIG. 9 is a right side elevational view of the water floatation device of FIG. 1; and,

FIG. 10 is a left side elevational view of the water floatation device of FIG. 1.
